UNITED STATES PATENT OFFICE.

CHARLES W. MANZEL, OF BUFFALO, NEW YORK.

LUBRICATOR.

No. 829,166.

Specification of Letters Patent.

Patented Aug. 21, 1906.

Application filed November 1, 1905. Serial No. 285,408.

To all whom it may concern:

Be it known that I, CHARLES W. MANZEL, a citizen of the United States, residing at Buffalo, in the county of Erie and State of New York, have invented a new and useful Improvement in Lubricators, of which the following is a specification.

This invention relates to a lubricator of the force-feed type having a plurality of pumps for delivering the lubricant to different parts of an engine or machine, the same being intended more especially for use on locomotives.

The principal object of my invention is the provision of a lubricator of the class which combines the advantages of simplicity, compactness, and comparatively low cost.

Further objects are to provide the lubricator with simple and convenient means for regulating the quantity of oil supplied by the same and for observing the feed when desired.

In the accompanying drawings, consisting of three sheets, Figure 1 is a front elevation of the lubricator. Fig. 2 is a side elevation thereof. Fig. 3 is a vertical central section of the same. Fig. 4 is a vertical section of the sight-chamber, taken through one of the oil-return passages. Fig. 5 is a horizontal section in line 5 5, Fig. 3.

Similar letters of reference indicate corresponding parts throughout the several views.

A indicates the body or reservoir of the lubricator, which is preferably rectangular, as shown, and provided with a removable front plate A'. In its top the reservoir has a filling-tube b, closed by a screw-plug b', the tube preferably carrying a tubular strainer b² for intercepting any foreign substance in the oil, as shown in Fig. 3.

In the lower portion of the reservoir are arranged one or more horizontal force-pumps C, which take the oil from the same and deliver it to the parts to be lubricated, the lubricator shown in the drawings having seven independent pumps adapted to supply the steam-cylinders, air-cylinders, and other parts of a locomotive. In the preferred construction shown in the drawings the plungers C of the several pumps are secured to and actuated by a common cross-head D, arranged within the reservoir and having forwardly-extending arms D', Figs. 3 and 5, provided with trunnions d. This cross-head is reciprocated by a depending bifurcated arm or

frame E, secured at its upper end to a transverse rock-shaft E' and having forked lower ends e, which embrace the trunnions d. The rock-shaft E' may be actuated by any suitable means, the preferred device being an air-motor E² of any approved type, which transmits the movements of its pistons to the rock-shaft by an arm E³, secured to the outer end of the shaft. Each pump-barrel is provided in its upper side with an inlet-port c, a suitable strainer c' being preferably applied over the several inlet-ports, as shown in Figs. 3 and 5.

In the discharge-passage of each pump C are a pair of spring-pressed check-valves f f'. The second check-valve f' is preferably arranged within a removable case or cage F, screwed into an opening in the front plate A' of the lubricator, as shown in Fig. 3. The discharge-ports f² of the several cases F communicate with descending delivery-passages f³, formed in a downward extension of the front plate A' and terminating, respectively, in nozzles f⁴, to which the usual oil-pipes are connected. The valve-cage F is provided in opposite sides of its reduced front end with passages f⁵, through which the oil enters the cage. The several descending passages f³ communicate with a common horizontal valve-case G, containing a rotary valve-plug G' for controlling the flow of the oil to the lubricated parts.

H indicates a sight-chamber arranged at the top of the lubricator on its front side and preferably formed by an enlargement at the upper end of the front plate A', as best shown in Figs. 2 and 3. The barrels of the several pumps C are connected with this sight-chamber by individual conduits or passages i, extending from the space between the two check-valves of each barrel to the upper portion of the sight-chamber. These conduits are preferably arranged on the inner side of front plate A', and their upper ends communicate with drip-nozzles i', which extend through the top of the sight-chamber and from which the oil falls in drops. This chamber is provided in its front wall with a transparent pane h, through which the oil-feed may be observed.

j, Figs. 3 and 4, represents passages which connect the bottom of the sight-chamber with the interior of the reservoir A and through which the oil discharged into said chamber is allowed to return to the reservoir.

K indicates a stop cock or valve arranged in the several ascending passages *i* for establishing or cutting off communication between the several pumps and the sight-chamber H. 5 As shown in Fig. 5, the rotary plug of this valve has a port for each of said passages.

A regulating piston or follower L is preferably combined with each pump barrel or cylinder for causing it to deliver a predetermined 10 quantity of oil to the part supplied by same. In the construction shown in the drawings each regular piston is fitted in an enlargement or chamber L', arranged on the upper side of the corresponding barrel and communicating therewith beyond the inlet *c*. The outward movement of the piston is limited by a stop or screw-threaded rod M, passing through a threaded opening in the top of the oil-reservoir and locked in position by a jam- 15 nut *m*. The spring of the first check-valve *f'* is so stiff that its resistance is greater than the weight or resistance of the regulating-piston L.

Upon the forward stroke of a pump-plunger 20 the corresponding regulating-piston L is raised by the pressure in the barrel until it strikes its stop M, the oil in the barrel entering the portion of the enlargement L' left vacant by the displaced piston. When the 25 regulating-piston is thus arrested, the continued pressure in the pump-barrel overcomes the spring of the check-valve *f'*, opening the latter and delivering a greater or less charge of oil through the discharge-passage 30 of the barrel, according to the extent of travel of the regulating-piston permitted by its stop. This piston has a uniform predetermined stroke, and the capacity of the pump-barrel is augmented more or less by its enlargement, 35 according as the regulating-piston is allowed to recede more or less by its adjustable stop. It follows that by increasing the capacity of the barrel a smaller quantity of oil will be pumped past its check-valves *f,f'*. 40 Thus if it is desired to supply the maximum quantity of oil, the stop M is adjusted to its lowest position, while if a smaller quantity is to be supplied the stop is raised to a greater or less extent.

50 When the lubricator is in its normal condition for supplying oil to the desired parts, the lower hand-valve G' is open and the upper hand-valve K is closed, so as to cut off the sight-chamber H from the pump-barrels. 55 The oil is now forced by the pumps past the check-valves *f,f'* and through the delivery-passages *f³*.

When it is desired to observe and regulate the feed of the pumps, the upper valve K is 60 opened, as shown in Fig. 3. The lubricant will be forced past the first check-valve of each pump and up through the conduits *i* and the drip-nozzles *i'* into the sight-chamber, whence it returns into the reservoir through the passages *j*, as before described. The spring of the

second check-valve *f'* of each pump is made stiff enough to cause the oil under these conditions to ascend through the passages *i* into the sight-chamber and prevent the oil columns in said passages from opening said valves and escaping into the delivery-passages *f³*.

The oil-reservoir is provided in one of its walls with a gage-glass N, seated in a rabbed plate N', which is screwed or otherwise 70 removably secured to the side of the reservoir. This glass forms the outer wall of a vertical chamber N², which normally communicates with the interior of the oil-reservoir by an opening or passage n, arranged 80 near the lower end of said chamber, the upper portion of the chamber having the usual vent *n'*. In the event of the glass being broken the opening or passage *n* is closed by a suitable plug *n²* to retain the oil in the reservoir until the broken glass can be replaced by a new one. When not in use, this plug may be screwed into an opening into the lower end of the plate N'.

By my improved construction a sight-feed, as well as a regulating device for the oil-delivery, is combined with each pump, permitting the several pumps to be regulated independently in accordance with the quantity of lubricant to be supplied to each part. At 90 the same time the construction is exceedingly simple and compact.

I do not wish to claim in this application the construction of the regulating device L M, as the same forms the subject of another application filed by me August 24, 1905, Serial 100 No. 275,515.

I claim as my invention—

1. The combination of an oil-reservoir, a pump supplied therefrom, a spring-pressed 105 check-valve arranged in the delivery-passage of the pump, a sight-chamber arranged above the level of the pump, a conduit leading from the portion of said delivery-passage on the inner side of said valve to the sight-chamber, the spring of said check-valve having sufficient resistance to support the column of oil in said conduit, and a cut-off valve arranged in said conduit, substantially as set forth.

2. The combination of an oil-reservoir, a 115 pump supplied therefrom, a pair of check-valves arranged in the delivery-passage of the lubricator one beyond the other, a sight-chamber, and a conduit connected with the portion of the delivery-passage between said 120 check-valves and leading to the top of the sight-chamber, substantially as set forth.

3. The combination of an oil-reservoir, a pump supplied therefrom, a pair of check-valves arranged in the delivery-passage of the 125 lubricator one beyond the other, a sight-chamber, a conduit connected with the portion of the delivery-passage between said check-valves and leading to the top of the sight-chamber, and a return-conduit connecting 130

the bottom of the sight-chamber with the reservoir, substantially as set forth.

4. The combination of an oil-reservoir, a pump arranged in the lower portion of the reservoir and supplied therefrom, spring-pressed check-valves arranged in the delivery-passage of the pump one beyond the other, a sight-chamber arranged near the top of the reservoir and provided with a drip-nozzle, an ascending conduit connected with the portion of the delivery-passage between said valves and leading to the drip-nozzle, the spring of the second or outer one of said valves having sufficient resistance to support the column of oil in said conduit, a cut-off valve arranged in said conduit, and a second conduit connecting the bottom of the sight-chamber with the reservoir, substantially as set forth.
- 20 5. The combination of an oil-reservoir, a plurality of pumps arranged in the lower portion of the reservoir and supplied therefrom, a sight-chamber arranged near the top of the reservoir and provided with a plurality of drip-nozzles, independent conduits leading from the delivery-passages of the respective pumps to said drip-nozzles, a return-conduit connecting the sight-chamber with the reservoir, and a cut-off valve common to all of

said first-mentioned conduits, substantially as set forth.

6. The combination of an oil-reservoir having a removable front plate, a plurality of pumps arranged in the reservoir and supplied therefrom, a sight-chamber arranged above the level of the pumps, individual conduits leading from the respective pumps to the sight-chamber, and a cut-off valve controlling said conduits; the sight-chamber, said conduits and said valve being carried by the removable front plate, substantially as set forth.

7. The combination of an oil-reservoir provided in the outer side of one of its walls with an upright chamber, and a removable gage-glass forming the outer wall of said chamber, the lower portion of the chamber communicating normally with the reservoir by a passage adapted to be closed by a plug in the event of the gage-glass being broken, substantially as set forth.

Witness my hand this 30th day of October, 1905.

CHARLES W. MANZEL.
